UNITED STATES PATENT OFFICE.

FRED S. PAYNE, OF BOSTON, MASSACHUSETTS.

APPARATUS FOR OPERATING ELEVATOR-DOORS.

No. 839,314.

Specification of Letters Patent.

Patented Dec. 25, 1906.

Application filed July 1, 1905. Serial No. 267,878.

To all whom it may concern:

Be it known that I, FRED S. PAYNE, a citizen of the United States, residing at Boston, in the county of Suffolk and State of Massachusetts, have invented new and useful Improvements in Apparatus for Operating Elevator-Doors, of which the following is a specification, reference being had to the accompanying drawings.

10 The invention relates to that class of door-operating devices in which the mechanical means for opening and closing the door are controlled by an electric circuit which is made and broken by the movement of the elevator-car and the action of the car operator.

20 My objects have been, first, to provide an apparatus which shall allow the door to remain normally closed unless the elevator-car is stationary at such doorway; second, to provide means controlled by the operator of the car for opening and closing the door; third, to provide means for causing the door to close upon the movement of the car away from 25 such door. I accomplish these objects by the means hereinafter specified and as illustrated in the accompanying drawings.

30 Figure 1 represents a partially-open door in an elevator-shaft with a portion of the 35 controlling mechanism. Fig. 2 shows such mechanism in position when the door is closed. Fig. 3 is a diagrammatic view of the electrical connections for the elevator-car controlling the operation of the mechanism shown in Figs. 1 and 2.

1 represents an ordinary door in an elevator-shaft.

2 is a rail. 3 and 3^a are contact-plates attached to said rail and located at such points within the elevator-shaft that one of such plates will be in contact with shoe 4 of car 5 whenever said car is opposite the corresponding doorway in said shaft. I preferably 45 make rail 2 continuous, so that it extends approximately the entire length of the elevator-shaft, and set plates 3 and 3^a into said rail, so that they will be insulated therefrom and with their outer surfaces flush with the 50 face of said rail. By so doing shoe 4, which is held in sliding contact with rail 2 by any suitable means, is allowed to successively make contact with plates 3 and 3^a without the jar which would otherwise be incident to the making of such contact by a rapidly-moving elevator-car.

6 represents an ordinary operating-lever within the elevator-car.

7 is a contact-plate on but insulated from lever 6.

8 is a contact-plate so placed as to be in contact with plate 7 when, and only when, lever 6 is in proper position for the elevator-car to remain stationary. In the accompanying drawings I have shown plate 8 affixed to but insulated from the casing surrounding the lower part of lever 6 and in the center of the segment traveled by said lever.

9 is a push-button. A convenient place to locate such button is in the handle of lever 6.

10 and 10^a are electromagnets having movable armatures 11 and 11^a, respectively.

12 is a valve having inlet-pipe 13 and outlet-pipes 14 and 15. Valve 12 is operated by lever 16, normally held in position by spring 17 or any similar device. Lever 16 is attached to armature 11.

18 is a cylinder within which is reciprocating piston 19. Pipes 14 and 15 enter cylinder 18, one at either end.

20 Bar 20 is pivoted at one end on door 1 and at the other on some stationary support attached to the side of the elevator-shaft. Connecting-rod 21 connects bar 20 with the cross-head of piston 19, which runs in guides 21^a.

25 The particular form of construction of the valve and other mechanical connection between armature 11 and door 1 is not essential to my invention, and I make no specific claim therefor. Any type of valve which will allow of a reciprocating action being imparted to a piston and any suitable form of connection between such piston and the elevator-door may be adopted. That shown herein is 30 simple in construction and operation and has the advantage of causing door 1 to remain closed and by using a rule-joint in bar 20 locked until magnet 10 be energized.

35 22 and 23 are the main supply and return wires, respectively, connected to the positive and negative poles of any suitable electric generator. Wire 22 connects with magnets 10 and 10^a by branch wires 22^a. Wires 24 and 24^a, respectively, connect contact-plates 3 and 3^a with magnets 10 and 10^a. Wire 40 23 connects with plate 8, and plate 7 is connected with push-button 9 by wire 25. Wire 45 26 connects said button with shoe 4.

50 When valve 12 is in normal position, the operating fluid will enter cylinder 18 through pipes 13 and 15, thereby forcing piston 19 into position shown in Fig. 2 and door 1

will be closed. Upon the stopping of the elevator-car before a door, plate 3 and shoe 4 or plate 3^a and shoe 4, as the case may be, will be in contact, as will also be plates 7 and 8. If push-button 9 be then pressed, the electric circuit will be completed by means of the wires and electrical connections hereinbefore described, the proper magnet will become energized, thereby actuating lever 16, which causes valve 12 to operate in reverse action, piston 19 will rise, and the door will be opened. If the electric circuit be broken at push-button 9 or by the starting of the elevator-car and the consequent disengagement of plates 7 and 8 or shoe 4 and plates 3 or 3^a, lever 16 will be returned to its normal position, as hereinbefore described, and the door will be closed. Should the car not stop at any doorway or the operator fail to press button 9, all doors will remain closed.

What I claim, and desire to secure by Letters Patent, is—

1. The combination with an elevator-car and its operating mechanism, including the operating-lever, and a door, of a plurality of contacts adapted to engage each other by reason of the movement of said car, a contact on said lever, a contact adapted to be engaged by the contact on said lever whenever said lever is in position to stop said car, a push-button, a magnet, means whereby said contacts, push-button and magnet are electrically connected, and means controlled by said contacts, push-button and magnet when so connected for opening said door.

2. The combination with an elevator-car and its operating-lever, of a movable contact actuated by said car, a stationary contact adapted to be engaged by said movable contact, a contact on said lever, a contact adapted to be engaged by the contact on said lever, a push-button and a magnet, all being within an electric circuit, a valve operated by said magnet and a motor controlled by said valve.

3. In combination with an elevator-door in an elevator-shaft and an elevator-car with its operating-lever, a contact in said shaft, a contact on said car adapted to engage the contact in said shaft, a contact on said lever, a contact adapted to be engaged by the contact on said lever whenever said lever is in position to stop said car, a push-button in said car and a magnet, said contacts, push-button and magnet being electrically connected, a valve operated by said magnet and a motor in mechanical connection with said door and controlled by said valve.

4. In an apparatus of the class described, an elevator-car, its operating-lever, a door, a contact carried by said car, a stationary contact engaged by said first-mentioned contact whenever said car is opposite said door, a contact on said lever, a contact engaged by the contact on said lever whenever said lever is in position to stop said car, a push-button,

said push-button, contacts and magnet being electrically connected, a valve controlled by said magnet, a piston controlled by said valve and means actuated by said piston for opening and closing said door.

5. In an apparatus of the class described, an elevator-car with its operating-lever, a plurality of doors, normally held closed, a stationary contact adjacent to each door, a contact carried by said car and adapted to engage the contact adjacent to the door to which said car is opposite, a contact on said operating-lever, a contact engaged by the contact on said lever whenever said lever is in position for said car to stop, a push-button, an electromagnet on each floor adjacent to its corresponding door, a valve on each floor controlled by said magnet, a motor on each floor controlled by said valve, means connecting said motor and door to which it is adjacent, and an electric circuit connecting said contacts, magnets and push-button; as and for the purposes hereinbefore set forth.

6. The combination with an elevator-car, its operating-lever and door in elevator-shaft, of a contact engaged by a contact on said car whenever said car is opposite to said door, a contact engaged by a contact on said lever whenever said car is stationary, an electromagnet, means controlled by the operator of the car for completing the electric circuit and energizing said magnet, and means controlled by said magnet for opening and closing said door.

7. The combination of an elevator-car, its operating-lever, a door, a contact carried by said car, a contact engaged by the contact on said car when said car is adjacent to said door, a contact on said lever, a contact engaged by said contact on said lever when said lever is in position for said car to stop, a magnet, means controlled by the operator of said car for completing an electric circuit through said contacts and magnet when said car is opposite said door, and means for causing said door to open when said electric circuit is completed.

8. The combination with an elevator-car, its operating-lever and a door in the elevator-shaft of a contact actuated by said car, a contact engaged by the contact on said car when said car is opposite said door, a contact actuated by said lever, a contact engaged by the contact actuated by said lever when said lever is in position for said car to remain stationary, a magnet, means controlled by the operator of said car for energizing said magnet when said car is opposite said door, means for causing said door to open when said magnet is energized and means for causing said door to close when said magnet is deenergized.

9. The combination of an elevator-car, its operating-lever, a door, a contact actuated by said car, a contact engaged by the contact actuated by said car when said car is oppo-

site said door, a contact actuated by said lever, a contact engaged by the contact on said lever when said lever is in position to stop said car, an electromagnet, means for completing an electric circuit through said contacts and magnet when said car is opposite said door, means for causing said door to open when said electric circuit is completed, and means for causing said door to close whenever said electric circuit is broken.

10. The combination with an elevator-car and its operating mechanism and a door, of a fixed contact, a contact actuated by said car so as to engage said first-mentioned contact whenever said car is opposite said door, a plurality of contacts so placed as to engage each other only when the mechanism for starting and stopping said car is in position for said car to stop, a magnet, means for completing an electric circuit through said contacts and magnet when said car is opposite said door and means controlled by said electric circuit for opening said door.

11. In an apparatus of the class described, an elevator-car with its operating mechanism, a door, a plurality of contacts so placed as to engage each other whenever said car is adjacent to said door, a plurality of contacts so placed as to engage each other whenever said car is stationary, a magnet, means controlled by the operator of said car for completing an electric circuit through said contacts and magnet when said car is opposite to said door, means for causing said door to open when said electric circuit is completed and means for causing said door to close whenever said electric circuit is broken.

12. In an elevator, the combination of a movable car, with a series of landings each having a door, controlling mechanism to start or stop the car at any adjacent landing, connections between the car and doors, operated partly by said controlling mechanism and partly by means operated by the operator of said car for opening any one of said doors at the option of the car operator, when said car is stationary at the landing where the door which it is desired to open is situated.

13. In an elevator, the combination of a movable car, with a series of landings each having a door, controlling mechanism to start or stop the car at any adjacent landing, connections between the car and doors, operated partly by said controlling mechanism and partly by means operated by the operator of said car for opening any one of said doors at the option of the car operator, when said car is stationary at the landing where the door which it is desired to open is situated.

ated, and means for causing said door to close at the option of the car operator.

14. In an elevator, the combination of a movable car, with a series of landings each having a door, controlling mechanism to start or stop the car at any adjacent landing, connections between the car and doors, operated partly by said controlling mechanism and partly by means operated by the operator of said car for opening any one of said doors at the option of the car operator, when said car is stationary at the landing where the door which it is desired to open is situated, and means for causing said door to close whenever said car starts away from said landing.

15. In an elevator, the combination of a movable car, with a series of landings each having a door, controlling mechanism to start or stop the car at any adjacent landing, connections between the car and doors, operated partly by said controlling mechanism and partly by means operated by the operator of said car for opening and closing any one of said doors at the option of the operator of said car when said car is stationary at the landing where the door desired to be so operated is situated.

16. The combination with the door of an elevator-well, a lock therefor, a car and its controller, of means intermediate the control device and lock whereby when the car is opposite the door with the control device in stop position, said intermediate means may be shifted to unlock the door, substantially as set forth.

17. The combination with the door and lock of an elevator-well, a car, controller, and means intermediate the lock and controller whereby the lock may be shifted when the car is opposite the door, of a device supported by the controller and operable to move said intermediate means only when the controller is in stop position, substantially as set forth.

18. The combination with the lock of an elevator-door, of a car and its controller, and means, including a device carried on the controller and operable at the will of the operator when the controller is in stop position, to shift said lock when the car is opposite the door, substantially as set forth.

In testimony whereof I have signed my name to this specification in the presence of two subscribing witnesses.

FRED S. PAYNE.
